UNITED STATES PATENT OFFICE.

ROGER J. BOYD, OF CHICAGO, ILLINOIS, ASSIGNOR TO THE FIRM OF CARSON, PIRIE, SCOTT & CO., OF CHICAGO, ILLINOIS.

PACKING-BOX.

1,329,577.

Specification of Letters Patent.

Patented Feb. 3, 1920.

Application filed November 29, 1915, Serial No. 64,020. Renewed November 10, 1919. Serial No. 337,056.

To all whom it may concern:

Be it known that I, ROGER J. BOYD, a citizen of the United States, residing at Chicago, in the county of Cook and State of Illinois, have invented certain new and useful Improvements in Packing-Boxes, of which the following is a specification.

This invention relates to improvements in packing boxes.

10 The object of the invention is to provide a simple and cheap packing box which may be made of paper or strawboard. Boxes of this kind have come into very general use on account of the expensiveness of suitable 15 wood for making the usual packing boxes and furthermore, boxes of the sort about to be described have certain advantages over wooden boxes in that their internal construction may be readily made such as to dispense with the usual packing material 20 such as excelsior, paper, etc.

A further object of the invention is to provide a box whose internal construction will be such that the articles packed therein will 25 be protected from shock in shipping or handling from all sides of the package or carton.

The present box is adapted particularly 30 for packing goblets or stem glasses, the construction being such that the space of the container is economized to the utmost while at the same time, keeping the articles separated from each other at all points as well as keeping them separated from certain 35 parts of the container, thus insuring absolute safety, from breakage in handling and shipping.

In the drawings,

40 Figure 1 is a perspective view of the box open, showing the top retaining section therein;

Fig. 2 is a vertical section of the box closed;

45 Fig. 3 is a perspective view of the packing section, removed, and Fig. 4 is a fragmentary perspective view of a corner of one of the retaining sections in normal position;

50 Fig. 5 is a grouped fragmentary perspective view showing the manner of recessing the lengthwise and transverse partitions which form the packing sections.

In the drawings, the numeral 1 designates the body of the box provided with end cover flaps 2 and side cover flaps 3. These flaps

are duplicated in every respect at the bottom of the box. 55

The numeral 4 designates a retaining section formed with end flanges 5 and side flanges 6, which flanges are cut away at the corners so as to render them capable of being bent at right angles to the flat portion of the section and the flanges are normally flared so that they will wedge in the box in assuming straight position, to firmly retain the section in the box, as shown in Fig. 2. 60 The numeral 7 designates another retaining section similar in all respects to the bottom section and this section is provided with side flanges 8 and end flanges 9, and is normally shaped as shown in the fragmentary view, 65 Fig. 4. Interposed between the two retaining sections, is a packing section 10, formed of a series of lengthwise partitions 11, and cross or transverse partitions 12. The lengthwise partitions are provided near 70 their opposite ends, each with two vertical slots 13, which extend for a little more than one-half the depth of the partition, and are open at their tops. The transverse partitions are provided with similar slots 14, 75 open at the bottom, so that when the lengthwise and cross partitions are placed together, the slotted portions interlock, to form compartments and when in position, both lateral and longitudinal movement of the partitions is prevented. 80

The transverse partitions are provided with slots 15 extending about one-half the width of the partition, which slots as shown in Fig. 3, alternate; that is to say, the slots 90 in the end partition are cut from the top, whereas, the slots in the adjoining partition are cut upward from the bottom.

There are shown in Fig. 2, in dotted lines, 95 stem glasses, illustrating the manner in which the stems of the glasses are held in the slots 15, and tightly embraced by the material of the transverse partitions at the edges of the slots, with the base of the glass occupying the space between the extreme ends 100 of the crosswise partitions and the end walls of the box when the packing sections are in place therein, as shown in the figure mentioned.

The operation in placing the glasses in the 105 packing section is quite simple. It is only necessary to remove the two inner cross partitions, when obviously the stems of the

glasses can be forced downward into the vertical slots 15 in the end partitions 12, and when they have reached their lowermost position and the bodies of the glasses rest upon the top of the retaining section 4, the other two inner partitions are forced into place, the recesses 15 in such positions, straddling and tightly holding the stem nearer the body of the glass. It will be noted that 10 lateral movement of the glasses will be prevented by this engagement of the cross partitions with two parts of the stem, thus keeping the bodies of the glasses slightly out of contact with the sides of the lengthwise partitions 11, it being preferred that the lengthwise sections shall be so spaced apart as to produce this result relative to a given size glass intended to be packed for shipment.

Obviously, to remove the glasses the inner 20 cross partitions are merely lifted out, when the glasses can be readily removed, and it will be further noted that the construction of the box is such that it can be used many times.

25 Having thus described my invention, what I claim is:—

1. A packing box comprising a body having folding portions adapted to form a cover, and a packing section in said box 30 comprising lengthwise and cross partitions spaced apart from each other, the cross partitions being provided with means for engaging the article to be packed to hold the same firmly between the lengthwise partitions, and to engage said article at a plurality of points at one end thereof.

2. A packing box comprising a body having folding portions adapted to form a cover, a packing section supported within 40 said box and separated from the top and bottom of the box, said packing section being composed of a series of lengthwise and spaced transverse partitions, the transverse partitions being provided with slots between

the lengthwise partitions, said slots extending a substantial distance through the depth of said transverse sections, the slots in one section being open at the top, while the slots in the adjoining section are open at the bottom, substantially as and for the purposes 50 set forth.

3. A packing box comprising a body having folding portions adapted to form a cover, a packing section in said box and separated from the bottom and top thereof, said 55 section comprising lengthwise partitions and spaced transverse partitions to engage one end of the article at a plurality of points, the end transverse partitions being within the ends of the lengthwise partitions, there 60 being in the transverse partitions, and between the lengthwise partitions, slots that in one partition are open from the top down, and in the adjoining partition from the bottom up, substantially as and for the purpose 65 set forth.

4. A packing box comprising a body having folding portions adapted to form a cover, a packing section within said box and separated from the top thereof, said 70 section comprising a series of lengthwise slotted partitions and crosswise slotted spaced partitions, whereby the partitions are locked together, there being additional slots in the transverse spaced partitions between 75 the lengthwise partitions, the slots in one transverse partition being open at the top, while the slots in the adjoining partition are open at the bottom, the transverse partitions being spaced apart to provide means 80 for engaging one end of the article at a plurality of points thereof.

In testimony whereof I affix my signature in presence of two witnesses.

ROGER J. BOYD.
